DESIGN FOR A CABLE CAR BODY

Edwin O. Roggenstein, Norwalk, Conn., assignor
to Elec-Trick Toys Inc., Utica, N. Y., a corpora-
tion of New York, Robert Groben, Utica, N. Y.,
as trustee in bankruptcy

Application October 18, 1947, Serial No 142,004

Term of patent 14 years

(Cl. D34—15)

To all whom it may concern:

Be it known that I, Edwin O. Roggenstein, a citizen of the United States, residing in Norwalk, county of Fairfield, and State of Connecticut, have invented a new, original, and ornamental Design for a Cable Car Body, of which the following is a specification, reference being had to the accompanying drawings, forming part thereof.

Figure 1 is a perspective view of a cable car body, showing the new design as viewed from the right-hand side, and showing the pulley wheel, cable and coupler in dot-dash lines for illustrative purposes only;

Fig. 2 is a top plan view of the cable car body;

Fig. 3 is a left-hand side elevational view thereof; and

Fig. 4 is a front elevational view thereof.
The dotted line showing in the drawing figures
is for illustrative purposes only.

I claim:

The ornamental design for a cable car body,
substantially as shown and described.

EDWIN O. ROGGENSTEIN.
